UNITED STATES PATENT OFFICE.

JACQUES SCHLUMPF, OF OBER-WINTERTHUR, SWITZERLAND.

DEVICE FOR AUTOMATICALLY ADVANCING AND ROTATING THE YARN ROLLERS OF
YARN-DYEING MACHINES.

Application filed July 23, 1923. Serial No. 653,332.

To all whom it may concern:

Be it known that I, JACQUES SCHLUMPF, a citizen of the Swiss Confederation, residing at Ober-Winterthur, Rychenbergstrasse 207, Canton Zurich, Switzerland, have invented new and useful Improvements in a Device for Automatically Advancing and Rotating the Yarn Rollers of Yarn-Dyeing Machines, of which the following is a specification.

This invention relates to a device for automatically advancing and simultaneously rotating the yarn rollers of yarn dyeing machines, wherein the yarn rollers for applying the strands of yarn turn around a vertical central axis and are fed forward periodically with an alternating direction of rotation according to the successive different treatments to which the yarn is to be subjected.

According to the present invention the direction of rotation of the yarn rollers is always varied automatically by a novel mechanism when the rollers are to be advanced one step; means are also provided by means of which the feed may be accelerated or delayed and the duration of the treatment of the yarn by acid, dye and so forth thus varied. As all the movements of the dyeing machine are effected automatically, the treatment of the dyeing machine are effected automatically, the treatment of the yarn is independent of supervision by the operator. The improved mechanism is simple and may easily be arranged to suit the various requirements.

The mechanism may also be applied to other textile machines having covered rollers for the hank yarn, for example, mercerizing machines.

In the accompanying drawings is illustrated by way of example one form of construction according to the invention wherein:

Fig. 1 is a side elevation of the mechanism.

Fig. 2 is a section on the line A—B of Fig. 1.

Fig. 3 is a section on the line C—D of Fig. 2, and

Fig. 4 shows diagrammatically a dyeing machine to be driven by the mechanism.

The mechanism is provided with a shaft 1, driven by a motor and has a bevel wheel 1^a

which engages bevel wheels 2, 3 which are 55 mounted rotatably on a shaft 4.

To the bevel wheels 2, 3 are respectively keyed spur wheels 5, 6, these spur wheels 5, 6 gearing with toothed wheels 7, 8 which are loosely mounted on a shaft 9, the actual 60 driving shaft, which is mounted on the casing 10 parallel to the second shaft 4. The toothed wheels 7, 8 thus rotate in opposite directions. The wheels 7, 8 are respectively provided on their opposing sides with clutch 65 faces, 11 and 12. Between these lateral clutch faces 11, 12 there is movably mounted a clutch 13 provided with two lateral clutch faces adapted to engage with the clutch 70 faces 11 and 12. The clutch 13 is axially 75 movable on a sleeve positively connected to the driving shaft 9 through which the latter is driven. The shaft 9 is rotated in one direction or the other according to whether the clutch 13 is clutched to the wheel 7 or to the wheel 8. The wheel 7 is provided with a second lateral clutch face 16 with which a lateral clutch face 17 of a spur 80 wheel 18 may be brought into engagement. The spur wheel 18 is axially movable on the 85 shaft 9 and is under the action of a spring which tends to bring the clutch faces 16, 17 into engagement. The wheel, or gear, 18 gears with a master spur wheel 20 which wheel is loosely mounted on the second shaft 90 4 and is provided with a lateral projection 21 engaging with a groove 22 in a ratchet wheel 23. The latter is loosely mounted on the hub of a bevel wheel 25 mounted on the shaft 4 and is provided with 95 a radial guide rib 26 which engages in an annular groove 27 in the spur wheel 18. In the position shown in Fig. 2 the guide rib 26 holds the wheel 18 out of engagement 100 with the clutch face 16 against the action of the spring 19. The ratchet wheel 23 is engaged by a pawl 28 which is pivoted on an operating lever 29, Fig. 3. The operating lever 29 is pivotally mounted on a bolt 30 of the casing 10 and is moved by a controlling cam 32 against the action of a spring 34. The controlling cam 32 is rigidly connected to the wheel 7. In the casing 10 is mounted a spindle 37 which can be adjusted by a hand wheel 35 and which is provided with a projection 36 against which the operating lever 29 is pressed by the spring 34.

According to the adjustment of the spindle

37, the movement of the operating lever 29 and thus the movement of the pawl 28 may be varied. The wheel 20 rotates by means of a pinion 40, a toothed wheel 41 which drives a shaft 44 having a cam drum 42. The latter is provided with a cam groove 43 in which engages a pin 44 on an operating lever 45 which is also provided with a pin 46 engaging with the clutch 13 of the 10 clutch mechanism 11, 12, 13.

The method of operation is as follows:—

When the driving shaft 1 is rotated the spur wheels 7 and 8 are rotated and with the wheel 7 the controlling cam 32 is moved 15 in a circle and at each revolution of the wheel 7 feeds the ratchet wheel 23 forwardly, the feed being to a greater or lesser extent according to the position of the spindle 37. When the ratchet wheel 23 has completed 20 about half a revolution the guide rib 26 releases the wheel 18 so that this will be moved to the right by the spring 19, Fig. 2; its clutch face 17 then engages with the clutch face 16 of the wheel 7 and the wheel 18 will 25 be rotated in the same direction as the wheel 7. The wheel 18 then rotates the wheel 20 and this drives the ratchet wheel 23 by means of the lateral projection 21 so that the guide rib 26, will re-engage with the 30 annular groove 27 and thus move the wheel 18 axially to the left against the action of the spring 19, and thus disengaging the clutch faces 16 and 17. The wheel 20 thus carries out a step by step movement and this 35 movement is transmitted by the bevel wheel 25 and the gear train 46, 47 to the rotary frame 48 carrying the bearings for the yarn rollers, the frame being moved step by step around a vertical sleeve 50. The toothed 40 wheels 40, 41 and therewith the cam drum 42 are always rotated through 180° so that the operating lever 45 is displaced and thus the clutch member 13 is brought into engagement either with the clutch face 11 or 45 with the clutch face 12 of the spur wheels 7, 8. The clutch 13 and thus the shaft 9 are alternately rotated in opposite directions. The rotations of the shaft 9 are transmitted 50 to the yarn rollers 58 (Fig. 4) by means of the gear 55, 56, 57, on which lie the yarn strands. These yarn rollers 58 are alternately rotated in one direction or the other, and the change of direction is produced automatically after each step by step feed 55 movement of the rotary frame 48. By adjusting the spindle 37 the period during which the operation of the rotary frame is to be effected or take place may be adjusted so that the yarn strands may be moved in 60 one direction or the other for any desired length of time and thus subjected to any particular operation for any desired length of time.

Having now particularly described and as-

certained the nature of my said invention 65 and in what manner the same is to be performed I declare that what I claim is:—

1. In combination with a frame mounted for rotation and a yarn roller having a shaft mounted on said frame, a shaft 4 geared to 70 said frame, a shaft 9 geared to said yarn roller, a power shaft, a pair of revolute elements loose on the third named shaft and geared to the power shaft for rotation in opposite directions, a clutch to lock either 75 of said revolute elements to the third named shaft, a lever 45 to actuate said clutch, a master gear, means actuated thereby to operate said lever, a gear 18 engaging the master gear, slideable on the third named shaft 80 and having a clutch member engageable with one of said revolute elements, a spring to move said gear to engaged position, a ratchet wheel 23 loosely mounted on the second named shaft having a cam 26 to move said last named gear to disengaged position, and also provided with a semicircular slot, said master gear having a pin arranged to operate in said slot, a lever having a pawl 85 engaged with said ratchet wheel, a spring to move said lever and pawl in one direction and a cam on one of said revolute elements to move said lever and pawl in the reverse direction and thereby impart step by step 90 rotation to said ratchet wheel. 95

2. In combination with a frame mounted for rotation and a yarn roller having a shaft mounted on said frame, a shaft 4 geared to said frame, a shaft 9 geared to said yarn roller, a power shaft, a pair of revolute elements loose on the third named shaft and geared to the power shaft for rotation in opposite directions, a clutch to lock either of 100 said revolute elements to the third named shaft, a lever 45 to actuate said clutch, a master gear, means actuated thereby to operate said lever, a gear 18 engaging the master gear, slideable on the third named shaft 105 and having a clutch member engageable with one of said revolute elements, a spring to move said gear to engaged position, a ratchet wheel 23 loosely mounted on the second named shaft having a cam 26 to move said last named gear to disengaged position, and also provided with a semicircular slot, said master gear having a pin arranged to operate in said slot, a lever having a pawl 110 engaged with said ratchet wheel, a spring to move said lever and pawl in one direction and a cam on one of said revolute elements to move said lever and pawl in the reverse direction and thereby impart step by step 115 rotation to said ratchet wheel, and means to predetermine the extent of movement of said lever. 120

In witness whereof I affix my signature.

JACQUES SCHLUMPF.
